ORTON C. LITTLE, OF MENASHA, WISCONSIN.

SLIDING SHOE FOR FURNITURE.

No. 827,806.

Specification of Letters Patent.

Patented Aug. 7, 1906.

Application filed March 15, 1905. Serial No. 250,175.

To all whom it may concern:

Be it known that I, ORTON C. LITTLE, a citizen of the United States, residing at Menasha, in the county of Winnebago and State of Wisconsin, have invented a new and useful Improvement in Sliding Shoes for Furniture, of which the following is a specification.

My invention relates to a device for use upon furniture-legs or upon other articles which it is desired to move a short distance instead of the common wheel-casters, whose faults are many, it consisting of a circular shoe for supporting the article to be moved, said shoe having a flat and smooth lower surface for sliding along upon the floor, its outer edge being curved upward, a centrally-arranged socket upon its upper side in which is fitted a globular body having a stem extending outward therefrom for connection with the furniture or article to be moved, said globular body and socket forming a ball-and-socket or universal joint whereby said shoe can assume any position relative to the article to be moved that is likely to occur.

Persons at all conversant with the usual wheel-casters are aware of some of their objectionable features, among which is the extremely small surface that a wheel presents for the support of the article to which the caster may be attached, which surface if it be up on a carpet or rug will often make a nearly permanent indentation that when uncovered will present an unsightly appearance. Another is that the wheel of the caster often fails to revolve, which is often for the reason that the wheel fails to assume a position parallel with the desired line of movement, and thereby causing difficulty in running the caster over a rug or over a threshold. Still another difficulty is that of lubricating both the wheel and its pivotal holder. These objections are all obviated in my invention. A large circular and flat surface is presented for the support of the article to which the shoe is attached, said surface being made very smooth and glassy, the outer edge of the shoe being curved upward, so that in sliding the shoe along on floor or carpet it can easily slide over slight obstructions, and the shoe and its stem being connected by means of a universal joint the shoe can easily assume the position required for sliding over quite an obstruction, and, furthermore, the ball and socket are at all times in a position for the application to them of a little oil for lubricating said joint.

My invention is illustrated in the accompanying drawings, in which—

Figure 1 is a plan or top view of the device as it appears in looking downward upon it, excepting that in the preferred form the ears for partially surrounding the ball of the universal joint are omitted and in place thereof a continuous wall surrounds the ball. Fig. 2 is a vertical section, upon the line *aa* of Fig. 1, of the sliding shoe and its socket and of the leg of a piece of furniture and a side elevation of a stem for connecting the shoe and furniture, the stem being provided with a globular end for working loosely within said shoe-socket. Fig. 3 is a side elevation of the sliding shoe with its socket in the preferred form and the globular end of the stem in said socket, the stem being shown in a vertical position by heavy lines and by dotted lines in an angular position upon opposite sides of the vertical. Fig. 4 is a side elevation of the stem for entering the furniture-leg with its globular end. Fig. 5 is a vertical section of the shoe and its socket as shown in Fig. 1, it being a modification of the socket as shown in Fig. 1 relative to the part of the shoe-socket which surrounds the ball, as shown in Fig. 4. Fig. 6 shows a modification of the form of the stem or part having the globular end for connection with the article to be moved. Fig. 7 is a plan of a housing for covering the ball-and-socket joint of the device.

Similar numerals indicate like parts in the several views.

1 indicates a circular disk having a flat lower side 1^a and a socket 2 or 2^a upon its upper side, the socket being adapted for receiving and holding therein the globular end 3, which is integral with the stem 4 or 4^a.

In the modification shown in Fig. 3, which is in the preferred form, the ball may first be formed as near spherical as possible, then covered with an adhesive molding sand or material, placed in the mold, and the material of which the shoe is formed pressed or poured into the mold around the ball to a point above its center and to a sufficient height for holding the ball therein, as shown in said figure. After waiting awhile for the cast to become of the proper condition for being handled upon manipulating the stem and working out the sand said stem, while it is securely held in the socket, can be turned to any required angle, as it is shown in dotted lines in Fig. 3.

The rod is intended to be of wrought iron or steel, and the ball may be formed upon its

end by drop-forging, or it may be cast onto the end of the rod. In Fig. 6 a modification of the form of the stem is shown for adapting it for connection with the article to which it is desired to apply it. The upper end is provided with a flange 6, through which screws may be inserted for securing the shoe in place.

A cover or housing 7 is shown in Fig. 2, as 10 it can be applied over the ball-and-socket joint for excluding dust, if so desired, and also for retaining the ball 3 within the socket, the housing consisting of a thin sheet of metal or other suitable material cut to the 15 desired form and made dishing. It is provided with a central perforation 8 of a diameter sufficient for allowing the stem 4 to assume an angular position with reference to the shoe. It may be provided with ears 10 for being bent over the outer edge of the shoe, as is shown in its plan in Fig. 7. Upon the stem in Fig. 2 a washer 11 is placed, it resting upon the shoulder 9, and the leg of furniture 12 is supported upon said washer 25 and upon the top of the stem 4.

I do not confine the making of the shoe to any one material, as it may be cast of a suit-

able metal and, if desired, enameled, or it may be formed in a mold of porcelain, glass, or other material that is adapted for it for 30 meeting the various requirements of the trade.

Having described my invention, what I claim, and desire to secure by Letters Patent, is—

In a sliding shoe for furniture, consisting of a circular, flat-bottomed disk having its outer edge curved upward and a socket centrally arranged upon its upper side, a stem adapted for being connected with the article 40 to be moved and having a globular body fitted to oscillate within said socket, the combination therewith of a housing, consisting of a sheet-metal plate of an inverted dishing form, a central perforation therein, and means 45 around its outer edge for its connection with the upper edge of said shoe by bending a portion thereof over said edge, substantially as described.
